DESIGN FOR A TEXTILE FABRIC

Oscar J. Cahn, New York, N. Y.

Application February 26, 1936, Serial No. 61,356

Term of patent 3½ years

To all whom it may concern:

Be it known that I, Oscar J. Cahn, a citizen of the United States, residing at New York, city, county, and State of New York, have invented a new, original, and ornamental Design for a Textile Fabric, of which the following is a specification, reference being had to the accompanying drawing, forming part thereof.

The figure is a plan view of a textile fabric showing my new design.

The design consists of alternate parallel diagonal stripes, one stripe being characterized by a group of closely spaced raised threads and the other stripe being characterized by a smooth surface penetrated by fine hair.

I claim:

The ornamental design for a textile fabric substantially as shown and described.

OSCAR J. CAHN.
